Primary Examiner — Karen E Eldridge Powers*(74) Attorney, Agent, or Firm* — QuickPatents; Kevin Prince(57) **CLAIM**

I claim the ornamental design for a men's underwear with seamless pouch, as shown and described.

DESCRIPTION

FIG. 1 is a perspective view of a men's underwear with seamless pouch, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.

The broken lines in the figures represent stitching, and are part of the claimed design.
